RENÉ PHILIPPE JACCARD, OF GENEVA, SWITZERLAND

CLOCK MOVEMENT

Application filed February 27, 1930, Serial No. 431,943, and in Switzerland August 20, 1929.

This invention relates to a clock movement and more particularly to spring driven clock movements of the kind in which the main spring is adapted to supply energy for a long period of time without necessitating to be reenergized.

It is an object of the invention to provide a spring actuated clock movement in which the power of the main spring is not transmitted directly to the train of wheels but to an intermediary spring means which is tensioned and actuates the escapement of the clock movement, the main spring being prevented from action and held in inoperative position as soon as the intermediary spring means is fully tensioned, but is released after the energy of the intermediary spring means has been consumed.

Other objects will appear from the following description of my invention.

In the drawings, illustrating a preferred embodiment of the invention and a modification thereof,

Figure 1 shows a fragmentary elevation of a clock movement according to the invention.

Figure 2 is a section along the line II-II of Fig. 1.

Figure 3 is a sectional elevation of a modification.

Figure 4 is a plan view thereof, partly drawn in section.

In Figures 1 and 2 the spring barrel 1 contains a powerful driving spring capable of supplying energy for a week, a month or even a year. The toothed ring 2 of the barrel 1 is in mesh with a pinion 3 which turns with the wheel 4 meshing with the two pinions 5 and 6. The shaft 7 of the pinion 6 carries a braking device consisting of a beam 8 keyed to the shaft 7 and having hinged thereto at 9 and 10 two L-shaped levers 11 and 12 of which the ends 11a and 12a are disposed in proximity of a disk 15. The pinion 5 turns with a wheel 13 meshing with a pinion 14 connected to the disk 15 which constitutes the stop member.

The disk 15 and the braking device 8, 9, 10, 11 and 12 are therefore both connected to the spring barrel by means of two movement transmission devices of different gear

ratio, the disk 15 turning with a much greater speed than the braking device. The wheel 16 is arranged to turn freely on the shaft 7 and is in mesh with the wheel 17 which drives the non-represented escapement device. Two springs 18 and 19 are disposed obliquely with respect to the shaft 7 and connect the wheel 16 to each one of the levers 11 and 12. Each of these levers has a lug 20 which lugs normally engage in a recess 22 formed by projections 21 provided on the hub of the wheel 16.

The manner of action of the described mechanism is the following: When the spring barrel 1 turns it causes the rotation of the braking device and of the stopping disk 15, this disk turning at a greater speed than the braking device. This device while turning, stretches the two springs 18 and 19 because the wheel 16 which is connected to the escapement device can not follow the movement of the braking device and the lugs 20 leave the bottom of the recesses 22 to slide on top of the projections 21, the levers 11 and 12 turning about their pivots 9 and 10 so that the lever ends 11a and 12a make contact with the disk 15 and since these levers turn slower than the disk and in opposite direction, the disk is stopped. Since this disk is geared to the spring barrel, this latter cannot turn any further and the main spring will not be deenergized further, while the braking member is also stopped. The wheel 16, which is placed under the action of the springs 18 and 19 which are in this moment energized, turns regularly and actuates the wheel 17. The recesses 22 provided on the hub of the wheel 16 turn also and come again into a position opposite the lugs 20, and the springs 18 and 19, since they are disposed obliquely with respect to the shaft 7, pull the levers 11 and 12 to make the lugs enter the recesses. Then the ends of the levers 11a and 12a disengage the disk 15 and the main spring can again start to run down.

The advantage of the described mechanism consists in that the disk 15 turns with a much greater speed than the spring barrel and therefore the braking device will find very little resistance for stopping the disk.

since the slightest contact of the lever ends 11a and 12a is sufficient to stop the spring barrel. The entire mechanism is very sensitive and works with very little loss of energy, and practically the two springs 18 and 19 are always energized to the same degree of tension. These springs have the double function of turning the wheel 16 which is connected to the escapement and of pulling the levers 11 and 12 to make the lugs 20 enter the recesses 22.

In the modification shown in Figures 3 and 4 the wheel 13 is driven by the spring barrel (not shown) and turns the pinion 14 which is secured to the disk 23 provided with an annular flange. The spring barrel also drives a sleeve 24 freely turning on the shaft 34 and to which is secured a beam 25. Two levers 28 and 29 are pivoted at the ends of the beam at 26 and 27. This beam and the levers constitute the braking device as an equivalent to the parts 8, 11 and 12 in Figures 1 and 2. The levers 28 and 29 are connected by means of springs 30 and 31 to a beam 32 integral with a sleeve 33 keyed to the shaft 34 upon which is also mounted a wheel 35 meshing with the wheel 36 which drives the escapement device. The levers 28 and 29 are provided with projections 37 and 38 which are normally engaged in the recesses 39 and 40 of the hub 33.

The operation of this embodiment is the following: The force of the main spring in the spring barrel turns the braking device and the drum 23 at different speeds. The braking device while turning stretches the two springs 30 and 31 because the beam 32 connected with the escapement device cannot turn as fast as the braking device. The projections 37 and 38 leave the bottom of the recesses and the levers 28 and 29 turn about their pivots 26 and 27 and make contact with the drum 23 which is immobilized and prevents the spring barrel from turning further. The wheel 35 then turns under the combined action of the springs 30 and 31 and of the escapement, the beam 32 and hub 33 turning with the wheel so that the recesses 39 and 40 come again opposite the projections 37 and 38 and the springs 30 and 31 pull the levers to make the projections enter the recesses and to free the drum 23.

I claim:

1. In a spring driven clock movement having an escapement, the combination of a spring barrel, a rotatable stop member therefor, a rotatable braking device coaxially mounted with the stop member and including pivotally mounted friction levers adapted to be engaged with, or disengaged from, said stop member, transmission means for operatively connecting said spring barrel to said braking device and to said stop member, the transmission ratio of the connection between the spring barrel and the braking device be-

ing different from that of the connection between the spring barrel and the stop member, an escapement actuating wheel, spring means connecting said friction levers to said escapement actuating wheel and urging the levers out of engagement with the stop member, and means operatively associated with said wheel to bring said levers in engagement with said stop member upon rotation of the braking device.

2. In a spring driven clock movement having an escapement, the combination of a spring barrel, a rotatable stop member, a rotatable braking device coaxially mounted with said stop member and including friction levers mounted to pivot in a plane perpendicular with the axis of said braking device and stop member and adapted to engage or disengage said stop member, transmission means for operatively connecting said spring barrel to said braking device and to said stop member, the transmission ratio of the connection between the spring barrel and the braking device being different from that of the connection between the spring barrel and the stop member, an escapement actuating wheel, spring means forming a yielding connection between said braking device and said escapement actuating wheel and urging the friction levers out of engagement with the stop member, and means operatively associated with said wheel to bring said levers in engagement with said stop member upon rotation of the braking device.

3. In a spring driven clock movement having an escapement, the combination of a spring motor, a rotatable disk driven by said spring motor, a rotatable beam also driven by said spring motor and coaxially mounted with said disk, braking levers pivoted on said beam and adapted to cooperate with said disk, a rotatable escapement actuating member coaxially mounted with said disk and said beam, auxiliary spring means connecting said braking levers to said escapement actuating member, said member being provided with cam forming recesses, and projections on said braking levers cooperating with said recesses, whereby relative movement between said escapement actuating member and said beam carrying the braking levers, due to excess of turning moment of said spring motor driven beam, urges said braking levers against said disk.

In testimony whereof I affix my signature.

RENÉ PHILIPPE JACCARD.
